(57) **CLAIM**

The ornamental design for a triangular three-way garment closure, as shown and described.

DESCRIPTION

FIG. 1 is a front perspective view of a triangular three-way garment closure showing our new design;

FIG. 2 is a rear perspective view of the triangular three-way garment closure;

FIG. 3 is a front elevation view of the triangular three-way garment closure;

FIG. 4 is a left side elevation view of the triangular three-way garment closure;

FIG. 5 is a top plan view of the triangular three-way garment closure;

FIG. 6 is bottom plan view of the triangular three-way garment closure;

FIG. 7 is a right side elevation view of the triangular three-way garment closure; and,

FIG. 8 is a rear elevation view of the triangular three-way garment closure.

Our triangular three-way garment closure includes a central triangular design and three surrounding fasteners, and is intended for use with lingerie, brassieres, and the like.
